UNITED STATES PATENT OFFICE.

WILLIAM HOFFMAN KOBBE, OF NEW YORK, N. Y., ASSIGNOR TO TEXAS GULF SULPHUR COMPANY, OF BAY CITY, TEXAS, A CORPORATION OF TEXAS.

SULPHUR TAPER.

Application filed September 15, 1922. Serial No. 588,335.

To all whom it may concern:

Be it known that I, WILLIAM H. KOBBE, a citizen of the United States, residing at New York city, in the county of New York, State 5 of New York, have invented certain new and useful Improvements in Sulphur Tapers; and I do hereby declare the following to be a full, clear, and exact description of the invention, such as will enable others skilled in 10 the art to which it appertains to make and use the same.

This invention relates to sulphur tapers and has for its object the provision of an improved sulphur taper.

15 Sulphur tapers are largely used for detecting the presence of ammonia gas, and more particularly the escape of ammonia gas in refrigerating plants, by-product coke ovens, and other systems and apparatus 20 where ammonia is employed or is present.

The sulphur taper consists usually of an appropriate foundation with which is associated a suitable amount of sulphur. In use, the taper is ignited and the sulphur dioxide 25 gas formed by the combustion of the sulphur is utilized to indicate the presence of ammonia gas and trace the source thereof by the dense white smoke or fumes which results from the chemical union of sulphur dioxide 30 gas and ammonia. Sulphur tapers are also of advantage where it is desired to produce a small quantity of sulphur dioxide gas for any purpose.

Heretofore, sulphur tapers have been generally 35 made with a foundation of cardboard, yarn, string, or the like. The cardboard foundation is objectionable because the sulphur very readily cracks off, and moreover, while burning the sulphur on the cardboard 40 melts and drips. Sulphur tapers made with a foundation of yarn or string are inconvenient to handle because of their flexibility, and indeed are practically useless, on this account, when it is necessary to poke the 45 taper into difficultly accessible places.

The present invention contemplates an improved sulphur taper in which the sulphur is appropriately carried by a foundation which is not destroyed at the temperature of burning sulphur, and which preferably retains its 50 original form during the burning of the sulphur. In carrying out this invention I have found a pair of twisted metallic wires with an appropriate fibrous material associated therewith admirably adapted as the

foundation for the sulphur taper. The wires constitute a suitable support which is not destroyed or altered in form by the burning of the sulphur, and the fibrous material constitutes an appropriate medium for insuring 60 the adhesion to the wires of the desired quantity of sulphur for the taper.

In the accompanying drawings I have illustrated what I now regard as the best modes of carrying out the invention. In 65 these drawings, Figs. 1, 2 and 3 are views of one form of sulphur taper embodying the invention; Figs. 4 and 5 are views of a modified form of the invention; and Fig. 6 is an explanatory view showing one application 70 of the sulphur in detecting the presence of ammonia.

Referring to Figs. 1, 2 and 3 of the accompanying drawings, there is represented a pair of relatively small soft steel wires 7 75 which are employed as the foundation for the taper. The fibrous material 8 which is preferably made from a cheap grade of cotton is secured between the foundation wires 7 by twisting them together in the manner illustrated at the region 9, where the wires have been shown twisted without having the fibrous material between them. As can be seen more clearly in Fig. 2, the fibrous material 8 is laid between wires 7 so that the 80 lengths of the fibers lie transversely with respect to the axis of the foundation. By arranging the fibers in this way a maximum wick-like attraction for the melted sulphur is obtained so as to better insure against 85 dripping while the taper is being used. This arrangement also facilitates the impregnation of the fibrous material with melted sulphur during the manufacture of the taper.

As shown in Fig. 3 after the foundation 95 7 with the fibrous material 8 secured thereto has been made, it is dipped in molten sulphur for a sufficient length of time to cause the sulphur to thoroughly penetrate the interstices between the fibers and, upon 100 removal from the molten sulphur bath and subsequent cooling, a relatively large amount of sulphur solidifies within and upon the fibrous material. The temperature of this molten bath should be kept slightly above 105 the melting point of sulphur for the reason that at this temperature the sulphur is in the form of a relatively thin liquid which readily and quickly penetrates and impregnates the fibrous material. The thorough 110

impregnation of the fibrous material with the sulphur is indicated at 10 and the general appearance of the finished taper is shown at 11.

5 In Figs. 4 and 5, which illustrate a modified form of construction, the foundation consists of a single metallic wire 12 which is laid straight rather than spirally as in the case of the foundation wire 7. The fibrous 10 material in this form of taper is braided about the wire 12 in any suitable manner but it is advantageous to use a rather loosely twisted thread of relatively large dimensions so as to form a porous braid about the 15 foundation 12 as indicated by reference numeral 13. It is advantageous to roughen the wire 12 as indicated at 14 in order to assist in retaining the braid upon it.

Either of the forms of sulphur taper described above, as well as other constructions which will appear to those skilled in the art, may be produced by an automatic machine in which, after the fiber has been secured to the foundation the product thus produced is continuously fed through a vessel containing molten sulphur at the proper temperature. In this way the sulphur taper material may be produced continuously and automatically and then be cut up to form 30 tapers of any desired length.

This improved sulphur taper of my invention possesses many advantages over sulphur tapers as previously constructed. In addition to the fact that my improved taper 35 will burn without any dripping of sulphur therefrom, which is in itself a distinct advance over the prior art, it may be used in many places which have hitherto been almost inaccessible. For example, inasmuch 40 as the foundation of this taper is preferably made of soft metallic wire, the taper may easily be bent into any desired shape and the sulphur being secured to the foundation by means of the fibrous material will not 45 crack off. As illustrated in Fig. 6, it may be bent so as to test for a leak on the rear side of a pipe or other object. It is, of course, very difficult and in some cases practically impossible to test for leaks located 50 in such places as this with the sulphur tapers in use at present because they do not pos-

sess any great amount of rigidity and in fact usually are limp and difficult to manage. Another feature of my sulphur taper which results from the employment of a relatively rigid foundation is its ability to be reversed; that is, after the taper has burned half way out, the person using it can grasp the end of the wire foundation from which the inflammable material has been burned 60 and by thus holding it the whole taper may be consumed. Sulphur tapers made in accordance with this invention will be found to burn for a much greater length of time per unit of length and diameter than the 65 tapers of the prior art for the reason that it is possible to put a greater amount of sulphur into a taper of given size when they are constructed in this manner.

I claim:—

1. As a new article of manufacture, a sulphur taper comprising a flexible filamentous foundation which remains rigid at the temperature of burning sulphur, and a fibrous material secured thereon, said material being 70 impregnated with sulphur.

2. As a new article of manufacture, a sulphur taper comprising a flexible filamentous foundation which retains its shape at the temperature of burning sulphur, and sulphur combined with a fibrous material and secured on said flexible filamentous foundation.

3. As a new article of manufacture, a sulphur taper comprising sulphur appropriately combined with a material which burns at the temperature of burning sulphur and carried on a foundation which retains a predetermined shape at the temperature of 85 burning sulphur.

4. As a new article of manufacture, a sulphur taper comprising a foundation of metallic wire, and a fibrous material secured thereon and impregnated with sulphur.

5. As a new article of manufacture, a sulphur taper comprising a combustible fibrous material twisted between a pair of metallic wires and impregnated with sulphur.

In testimony whereof I affix my signature.

WILLIAM HOFFMAN KOBBE.
